UNITED STATES PATENT OFFICE.

EDWARD E. GOLD, OF NEW YORK, N. Y., ASSIGNOR TO GOLD CAR HEATING & LIGHTING COMPANY, OF NEW YORK, N. Y., A CORPORATION OF NEW YORK.

HEATING SYSTEM.

1,146,865.

Specification of Letters Patent. Patented July 20, 1915.

Application filed September 30, 1908. Serial No. 455,470.

To all whom it may concern:

Be it known that I, EDWARD E. GOLD, a citizen of the United States, residing in the borough of Manhattan, city, county, and State of New York, have invented certain new and useful Improvements in Heating Systems, of which the following is a specification.

This invention aims to provide improvements in heating systems especially adapted to the heating of railway trains by steam, and in which the temperature may be automatically and very sensitively controlled.

Preferably the apparatus involves only a slight modification of the apparatus now in general use on railway cars, so that existing systems may be very cheaply and quickly changed to secure the advantages of the new system.

Other points of advantage are referred to in detail hereinafter.

The accompanying drawings illustrate embodiments of the invention.

Figure 1 is a diagrammatic view showing the principal parts in vertical cross-section; Fig. 2 is a longitudinal section through the upper part of a car showing a part of the mechanism of Fig. 1; Fig. 3 is a perspective view of another system embodying the invention; Fig. 4 is a horizontal section through the inlet pipe and connected parts of Fig. 3; Fig. 5 is a perspective view of another apparatus embodying the invention; Fig. 6 is a cross-section of the thermostat of Fig. 5; Fig. 7 is a perspective view of another embodiment of the invention; Fig. 8 is a sectional view illustrating a modification of a part of Fig. 7; Fig. 9 is a perspective view of another embodiment; Figs. 10 and 11 are respectively an elevation partly in vertical section, and a plan partly in horizontal section of another apparatus embodying the invention; Figs. 12 and 13 are perspective views of systems showing adaptations of the invention to a so-called "indirect" heating system; Fig. 14 is a vertical sectional view of a discharge pipe and adjacent parts, showing a slightly modified embodiment of the invention; Fig. 15 is a cross-section of a part of another system embodying the invention; Fig. 16 is a cross section of a gravity valve which forms part of some of the systems shown in the other figures.

Referring to the embodiments of the invention illustrated, Fig. 1 shows at A and B the double floor of a car. The train-pipe C

runs lengthwise of the car and carries steam at any suitable pressure, generally reduced from that in the locomotive boiler to 40 to 60 pounds. The steam passes from the train-pipe to radiating systems at opposite sides of the car by way of branches D. The radiating system is indicated by an upper pipe E which first receives the steam, and a lower return pipe F which conveys the steam and hot water of condensation through a branch G to the discharge pipe. In one form of this system the branch G terminates in a vertical thermostatic trap which is designated as a whole by the letter H. This trap includes a trap valve J, in some cases controlled only automatically through a rod K and thermostatic member L, and in other cases having also a hand-operated stem M by which the valve may be manually operated, a small amount of lost motion being provided between the valve and the stems K and M. Ordinarily the trap includes also a blow-off valve N manually operated through a stem O. The trap valve J discharges steam through a pipe P at the lower end of which the thermostatic member L is carried. The member L is exposed to the atmosphere outside of, that is below the car, so that in cold weather it acts quickly to open the thermostatic valve and allow a frequent escape of the water of condensation. The water and steam passing down the pipe P reheat the member L, expand it, usually by converting its liquid content to vapor, and cause the closing of the valve J to prevent waste of steam. The pressure in the radiating system is maintained the same as that in the train-pipe. Or in some cases the branch between the train-pipe and the radiating pipes is provided with a pressure reducing valve Q which can be set to maintain any desired pressure up to the limit provided by the steam in the train-pipe. The blow-off valve N is opened to provide for the escape of air in the pipes when they are being filled with new steam, and for other purposes where it is desired to blow through the pipe, as in cleaning it out, etc. The steam escaping from the blow-off valve passes down through the pipe R which surrounds the thermostat pipe P. This permits of the warming of the parts to prevent and get rid of ice forming in the thermostat pipe or upon the thermostat itself, by opening the blow-off valve for a short time.

It is desirable in some cases where only a

gentle warmth is necessary, to utilize the steam at substantially atmospheric or lower pressure, and this invention provides a means for securing such an operation, preferably though not necessarily in the same apparatus in which an operation under pressure may be secured whenever the weather necessitates it. The apparatus of Fig. 1 is such an interchangeable system, and is capable of being so operated as to work at approximately atmospheric pressure, admitting just steam enough to keep the radiating pipes filled entirely or to any desired extent; the quantity of steam admitted being under control of a thermostat subject to the influence of the steam or water of condensation after it escapes from the apparatus, and of the external atmosphere, and preferably also being under control of another thermostat influenced by the temperature of the air in the car; or it may be operated according to the ordinary pressure system, utilizing either the pressure of the train-pipe or a suitably reduced pressure; and the change from one mode of operation to another can be effected with the greatest ease.

The automatic admission valve is indicated as a whole by the letter S, and may be of various styles. In Fig. 1 a pair of expansible vessels T and U are provided, each communicating with a body of a fluid preferably a liquid such as ether or alcohol which vaporizes at a comparatively low temperature. By using one fluid or another the apparatus can be made to operate with the radiating pipes only partially or entirely filled with steam, as is desired. The common elastic lower wall of the vessels T and U actuates the stem V so as to close a valve W which is normally held up from its seat by a spring X. The steam on the education side of the valve also has admission to the under sides of the diaphragm to hold the valve open until the pressure of the vaporized thermostatic liquid becomes sufficient to close the valve; but in this respect the details may be varied without departing from the principle of the invention. A strainer Y on the inlet side of the valve tends to prevent its becoming clogged with dirt. A manually operated stem Z projects through the end of the casing opposite the expansible vessels, and permits of forcing the valve up from its seat and positively holding it open. This is an advantage in the operation of atmospheric pressure systems in the initial heating of the car. Where the admission valve is entirely automatic it closes so soon after the admission of steam that the first heating of a cold car is very slow. By the use of a valve which can be held open by hand, the steam may be run through the pipes for a long enough time to warm the car, after which the normal automatic operation may be resumed.

Means may be provided accessible from within the car for effecting this positive opening of the admission valve. In fact the entire valve and connected mechanism may be within the car, as in the mechanism 70 in Fig. 4, for greater convenience in effecting this operation.

The arranging of the automatic supply valve between the train-pipe and the piping within the car, as shown especially in Fig. 75 1, is an important feature of this invention, and is rendered possible especially because of its automatic nature. The train-man will seldom have occasion to do more than open the usual stop-valve within the car, 80 after which the quantity of steam adjusts itself automatically to the demand occasioned by the rapidity of condensation in the radiating pipes. By arranging this automatic supply valve outside of the car, or at 85 least at a point between the train-pipe and the piping within the car, several advantages are obtained. The piping within the car does not ordinarily have to stand the high and variable pressures of the train-pipe, and there is ordinarily no pipe in the car having the extreme heat of the train-pipe so as to burn passengers or their clothes coming into contact with it. There is a third advantage in the matter of convenience, it being a question of some difficulty to find a good location within the car 95 for the automatic supply valve, this being somewhat larger than ordinary hand valves.

The expansible vessel U may be influenced 100 from any desired point in the piping through which the steam passes. Preferably as shown in Fig. 1 it is controlled by the steam or hot water at the lower end of the discharge pipe after it leaves the radiating 105 system, and by the atmospheric temperature. In order to make the system readily convertible from high pressure to atmospheric pressure, and vice versa, a chamber *a* is provided upon the outside of the blow-off pipe 110 R at a point below the floor of the car, this chamber being in communication with the expansible vessel U by means of a pipe *b*. The exposure of the thermostat to the air outside of the car insures its acting more 115 quickly when the steam is not admitted fast enough, thus giving a more sensitive and a better regulation. In order that the outside temperature shall not too greatly restrict the influence of the temperature of 120 the piping, the outer wall *c* of the chamber may be covered with a lagging *d* of wood, asbestos, or other non-conductor, and to any desired extent.

The operation of the mechanism thus far described is as follows:—Suppose the ordinary trap valve *J* to be without a manually controlling spindle *M*, or that this spindle be set to permit the automatic operation of the valve, then by opening the blow-off valve 125 130

N the system will operate under atmospheric pressure; and by closing this valve it will operate under high pressure (train-pipe or regulator pressure). The change 5 from one system to the other is therefore accomplished by the simplest possible operation. When the blow-off valve N is shut the thermostat will always be so cool that the admission valve will be held open by 10 its spring and the ordinary pressure operation will ensue. Upon opening the blow-off valve N the greater part of the steam will escape through this valve and will expand the vessel U to limit the admission of steam. 15 The steam and hot water passing down the blow-off valve will heat the regular thermostatic member L sufficiently to maintain the trap valve J closed. Or if the weather should be so cold as to open this valve it 20 will carry out only a small quantity of steam compared with that which will pass out through the freer opening of the blow-off valve. And if this escape of steam through the trap valve be objectionable, it may be 25 manually closed by turning the stem M.

Provision may be made for closing the valve J by the same operation which opens the blow-off valve and for releasing the valve J to permit its automatic operation by 30 the same manipulation which closes the blow-off valve. For this purpose a pinion e may be provided engaging pinions f and g upon the valve stems O and M respectively. When the stem O is turned therefore 35 to lift the blow-off valve clear of its seat, the stem M may be turned in the same direction to lift the valve J against its seat.

Under either high pressure or atmospheric pressure operation, if the car should be 40 closed for a long time and become too hot, the admission valve will be automatically closed by means of the expansion of the fluid in the vessel T. For this purpose the chamber of the vessel T communicates 45 by a pipe h running along the floor and up the side wall of the car with a pipe j arranged in the upper part of the car as shown best in Fig. 2. This pipe is preferably corrugated to expose a large radiating surface to the air in the car, and is slightly inclined downward and carries a quantity of the thermostatic fluid, the lower part of 50 which is in the vessel T. The upper end of the pipe j is provided with a chamber k which provides the necessary air space for elastic expansion. The roof of the car is indicated at l, and the upper windows at m. The separate thermostatic operation through 55 the pipe j may be omitted, and the effect of the temperature within the car secured by arranging the thermostatic chamber a around the piping within the car slightly in advance of the discharge pipe as, for example, in Figs. 5 and 6. In this case the thermostatically controlled admission valve

also is preferably arranged within the car. Whether both these parts, the admission valve and the thermostatic mechanism for controlling it, be placed both within or both without the car, there is a great advantage 70 in placing them both upon the same side of the floor or similar partition of a chamber, in the ease with which existing systems may be modified to secure the advantages of the invention. For example in order to 75 convert the ordinary pressure system into an interchangeable system, it is only necessary to detach the lower part of the blow-off pipe R and introduce a section having a chamber a; and to break the branch D which 80 admits steam from the train-pipe and insert therein the automatic admission valve S with proper connections to the chamber a. Or instead of a new section of piping containing a chamber a, a jacket or coil might 85 be applied to the original pipe. The automatic admission valve and thermostatic mechanism for governing it, may therefore constitute a complete combination adapted to be applied to existing systems. 90

The invention is applicable to various methods of heating, and it will be understood that the terms "radiating system" and "radiator" refer to a variety of apparatus. For example an indirect system may 95 be used, the steam pipes from the train-pipe passing into coils of water to heat the same, the water being then circulated in order to heat the car; this system being referred to in more detail hereinafter. And the thermostat may be actuated either by the water 100 of such a system or by steam.

In the diagrammatic illustration, Fig. 3, the automatic admission valve S is arranged within the car, the position of the floor being indicated by the dotted lines A B, and the chamber carrying the thermostatic fluid exposed to the heating medium consists of a coil a' passing around the lower part of the blow-off pipe R. The blow-off valve has a stem O, but the trap valve is not provided with any stem for manual operation. It is only necessary to turn the stem O in one direction or in the other to convert the system into an atmospheric pressure or a train-pipe pressure system respectively. A stop valve n is preferably provided in the inlet branch D between the train-pipe and the radiating pipes. The automatic admission valve is shown in detail in Fig. 4. It differs 110 from that in Fig. 1 in that it contains only the expandible vessel U controlled by the temperature of the heating medium, this vessel being in an outer casing o with a removable end p to permit withdrawal and insertion of the diaphragm; and in the provision of an adjusting screw q for adjusting the pressure upon the valve. 115

In the system shown in Fig. 5 instead of the vertical trap of the previous figures, 120

there is illustrated a T-trap H' with a blow-off valve N' at the bottom and a gravity trap r at the opposite side of the inclined discharge pipe s. This is a common arrangement. The thermostatic admission valve S in this case is controlled by the branch G which leads to the discharge pipe, a portion t of which is provided as shown in Fig. 6 with a steam passage u and a chamber a for the thermostat fluid. This apparatus it will be observed may be applied very readily to existing systems, and is entirely on the inside of the car. For this reason a less volatile thermostatic liquid should be used than in the apparatus of Fig. 1. In this construction the admission valve is arranged close to and nearly above the chamber carrying the thermostatic liquid, so that the connecting pipe b shall be inclined upward as much as possible, and so as to cause all or nearly all of the thermostatic liquid when it condenses to run down into the heating chamber a. The same arrangement is desirable in all constructions so as to insure the thermostatic liquids being subjected to the desired temperature. The construction of the double section of pipe t is substantially the same as that which has been used for storage heaters, and may be modified in any desired way to adapt it to the present apparatus.

In the construction shown in Fig. 7 the admission valve is controlled from a coil a' passing around a pipe v which is screwed into the lower end of the blow-off valve N', the valve S being inside the car and the other details being as in Fig. 5. The change from atmospheric pressure operation to higher pressure operation is effected by opening and shutting the blow-off valve N'. The invention in its broadest aspect is applicable not only to an interchangeable system, that is one operated either at atmospheric pressure or at higher pressure, but is applicable largely also to simple atmospheric pressure systems. Such an application of the invention is shown in Fig. 9, in which the automatic admission valve S is controlled by a chamber, a coil a' in the present case, around a discharge pipe w. There is no trap or other means for holding back the steam under pressure. Consequently the steam would always be at approximately atmospheric pressure, and the quantity of steam admitted will be controlled automatically by the location of the chamber carrying the thermostatic fluid, by the nature of the fluid, and by its degree of exposure to the outside temperature; or manually by the valve stem Z. Fig. 8 represents a simple modification of Fig. 7, in which the blow-off valve N' instead of being in an extension beyond the branches leading to the traps H' and r, is located in the same fitting x from which these branches lead to the traps. An open

pipe v carries the coil a' containing the thermostatic fluid, and which is in communication with the admission valve through the pipe b. A modification is shown here in the corrugating of the pipe v to provide a larger degree of contact with the coil a' carrying the thermostatic liquid.

The expansible member is not necessarily arranged within the casing of the admission valve. This expansible member may be arranged close to the point whose temperature controls the valve, and the movement may be transmitted to the valve mechanically. Such a construction is illustrated in Figs. 10 and 11. The admission valve S in this case has its stem V extended through a protecting pipe y to the expansible member U which is mounted directly upon the chamber z of half round cross-section and adapted to be bolted upon the blow-off pipe R by means of flanges at the sides.

Fig. 12 illustrates the application of the invention to an indirect heating system such as is commonly used for heating sleeping cars. The steam from the train-pipe C passes through the branch D to a double coil 2 the outer pipe of which is in communication with the water admission and discharge pipes 3 and 4, the water circulating from the pipe 4 by way of pipe 5 and radiator 6 and returning to the inlet pipe 3. The steam passes into the inner pipe of the coil through the small pipe 7 and out through the pipe 8 and thence to the discharge pipe s identical with that illustrated in Fig. 5 and carrying the same traps and blow-off valve N'. In order to apply the system here, I have shown an automatic admission valve S inserted into the steam admission pipe within the car and controlled by a body of thermostatic fluid extending into the chamber a which surrounds an extension v below the blow-off valve. By opening or closing the blow-off valve the system is made to work as an atmospheric pressure or a high pressure system at will. Such an interchangeable system is of especial value in connection with an indirect heating system. A serious difficulty experienced with atmospheric pressure systems in attempts to use them with indirect systems, lies in the difficulty of bringing the water in the radiating pipes and connected parts up to a sufficient temperature in a reasonably short time. This difficulty, which is a very serious one in practice, is overcome by applying the interchangeable principle to the indirect system so that the steam may be operated under pressure until the water is brought to a working temperature, and the heat and circulation may thereafter be maintained in moderate weather by working with steam at atmospheric pressure.

Instead of changing from an atmospheric pressure to a high pressure system by

manipulating a blow-off valve, the same change may be effected by manipulating the hand stem Z of the admission valve S if the thermostatic mechanism be so located as to be influenced by the temperature of the steam either in the pipe of the ordinary high pressure trap or in the piping in advance of the trap. For example in Fig. 1, if we suppose the location of the chamber a and the nature of the thermostatic fluid within it to be such that the passage of steam through the discharge pipe P of the trap will expand the thermostatic fluid sufficiently to operate the admission valve S , then it will be observed that the mere manipulation of the stem Z of the admission valve will effect the desired change from one system to another. If the admission valve be forced open and held so, the hot steam will first pass out through the trap and will in a short time actuate the valve thereof to close the system and allow a pressure to occur, opening only at intervals to purge the water of condensation, as usual. If now the admission valve stem Z be withdrawn to permit automatic operation of the valve, then upon the first opening of the trap valve the steam passing through the trap will close the admission valve, and not enough steam will pass through the trap thereof to re-close the trap valve. The discharge end of the system will be open to the atmosphere, and the regular atmospheric operation will be continued. No blow-off valve and no hand manipulation of the trap valve are necessary in this case.

The system shown in Fig. 5 is especially adapted for this mode of operation. The blow-off valve N' will ordinarily be closed or may be omitted. Then when the admission valve stem Z is manipulated to hold the valve S open, the system will operate like the ordinary pressure system. When the stem Z is screwed outward to free the admission valve, the latter will be controlled by the temperature of the steam in the branch G leading to the discharge, the supply of steam becoming a function of the temperature within the car, and of the rate of condensation and cooling within the radiating system. The trap r opens by the fall of pressure in the system. The pressure regulating valve Q of Fig. 1 may be interpolated in the admission pipe of this system, either in addition to or as a substitute for the stop valve n ; and in fact this pressure regulator may be used equally with any of the systems here described.

The same principle of control and of changing from a high pressure to a low pressure system, may be applied to indirect heating, for example in the manner shown in Fig. 13. In this case the vessel a carrying the thermostatic fluid is applied to the branch 8 of the steam piping which leads

to the discharge pipe, and the admission valve S is placed in the admission pipe 7 adjacent to and above the pipe 8 ; both being within the car and at points where they can be easily introduced upon systems already in use. The blow-off valve N' being normally closed, the mere screwing in or out of the admission valve stem Z determines whether the system shall operate under atmospheric pressure or under higher pressure.

The fluid pressure operated valve which is preferably used to control the admission, may be of any known or suitable type.

Instead of arranging the blow-off pipe and the trap in proximity to each other as in Fig. 1, they may be separated so that the blow-off pipe carrying the thermostatic fluid shall be beyond the objectionable influence of the steam passing through the trap when the system is working under pressure. See for example Fig. 7.

The application of the atmospheric pressure principle in the same system in which there is a blow-off valve is of great advantage. Where such systems have been tried the pipes have been always open and the steam therein always under atmospheric pressure or substantially so, and there could be no blowing out of the pipes. Consequently, especially when cars are left upon sidings or similar situations, there have been accumulations of water in the pipes and freezing, which involves great delay and trouble. Where a blow-off valve is provided, however, it is only necessary to shut this valve long enough to accumulate a pressure of steam in the radiating pipes, holding the admission valve positively open if necessary; then upon the opening of the blow-off valve the steam will rush through the pipes and blow out all water or dirt in the pipes.

The application of the invention to heating apparatus already in use, is facilitated by carrying the thermostatic fluid in a vessel preferably having rigid walls, which can be applied easily to the point at which the heating medium is to be utilized, and in which a pressure is generated which is transferred to an expandable vessel or yielding member at the admission valve a greater or less distance away from the point at which the heating medium is applied. See Figs. 1, 3, and others. A very simple application of this system is illustrated in Fig. 14 in which the vessel carrying the thermostatic fluid consists simply of a pipe a^2 introduced into the discharge pipe v of the system. This pipe is nearly filled with alcohol or other thermostatic liquid, is fastened by screwing into a ring 20 cast or otherwise fastened in the pipe v , and has its upper end guided by a similar nonthreaded ring 21 . In order to have the advantage of a partial exposure to the atmosphere, the pipe may be made of a

length to extend downward out of the lower open end of the discharge pipe *v*. Or the degree of exposure to the atmosphere may be made adjustable by applying a cover or shield such as the sheet-metal pipe 22 which is supported by a flange from the lower end of the discharge pipe *v* and which may be slid up on the discharge pipe and set at any desired elevation by a set-screw 23. Instead of being a simple pipe the vessel *a*² may be made of any suitable shape which is adapted to be easily set into the open lower end of the discharge pipe *v*. The same principle may be applied in introducing the thermostat at a point above the end of the system. For example, instead of using the double pipe *t* of Fig. 6, a pipe *a*³, Fig. 15, provided with spacing lugs 24 may be placed in the horizontal pipe *G* which leads to the discharge and may contain the thermostatic fluid, the connecting pipe *b* passing through the pipe *G*.

The operation of the gravity trap *r* shown in Fig. 5 and others will be more fully understood from Fig. 16 which shows a transverse section. The valve 25 closes forwardly against its seat 26 and is held closed as long as there is any substantial pressure of steam within the pipes. The stem 27 of the valve, however, is provided at its outer end with a weight 28 which tends to tilt the valve and which succeeds in tilting it as soon as the pressure within the pipes falls to approximately that of the atmosphere; which tilting opens the valve sufficiently to let out steam and water of condensation, and, in case of any vacuum, to let in air. It will be understood, therefore, referring to Fig. 5, that as soon as the admission valve is automatically closed and the pressure in the system falls by reason of condensation of the steam, the valve *r* will provide an opening so as to insure the maintenance of communication with the atmosphere and the escape of condensation water and any steam which reaches the end of the pipe. The pipe 29 (Fig. 16) is a branch in communication with the discharge pipe *s* of the system.

No claim is made in the present application to the use of the gravity valve of Fig. 16 or to the indirect heating system described except in so far as these features are included in the generic claims hereinafter,—said features being claimed in my applications No. 523,997, filed October 22, 1909, and No. 544,028, filed February 15, 1910.

What I claim is:—

1. A steam heating system including a supply valve and means for operating said valve, and thereby controlling the supply of steam, by the temperature at a determined point in the system, and means for positively

holding said valve open and rendering said controlling mechanism inoperative. 65

2. A steam heating system including an automatic discharge trap, a blow-off valve, radiating pipes at the end of which said trap and blow-off valve are located, thermostatic means controlled by the temperature of the heating medium passing through said blow-off valve and controlling the rate of admission of steam to the radiating pipes, and connecting means between said blow-off valve and said discharge trap for positively closing the trap when the blow-off valve is opened and releasing the trap to permit its automatic operation when the blow-off valve is shut. 75

3. A steam heating system including an admission valve, means for thermostatically controlling said valve to maintain a desired quantity of steam in the radiating system, and means for holding said valve open and rendering said controlling means ineffective 85 so as to permit the uncontrolled passage of steam into the radiating system.

4. A steam heating system including an admission valve, means for automatically controlling said valve to maintain a desired 90 quantity of steam in the radiating system, and means for rendering said controlling means ineffective and permitting the uncontrolled passage of steam into the radiating system, in combination with a trap at the 95 end of the radiating system adapted to purge the system at intervals and to automatically close when steam in substantial quantity escapes through it.

5. A steam heating system including an automatic discharge trap, a manually operated blow-off, an automatic admission valve controlled by the temperature adjacent to the discharge end of the system so as to limit the admission of steam when the blow-off is open, and means for positively holding said admission valve open to prevent the automatic operation of said admission valve. 100

6. A steam heating system including an admission valve, means for automatically 110 controlling the same, means for positively holding said valve open, and an automatic pressure regulator near the admission end.

7. A steam heating system including an automatic discharge trap, a blow-off, an 115 automatic admission valve controlled by the steam passing through said blow-off, and means for holding said admission valve open to prevent its automatic operation.

In witness whereof, I have hereunto signed my name in the presence of two subscribing witnesses.
